CUTICLE PENCIL

Ray K. Gregory, Berkeley, Calif.

Application January 17, 1938, Serial No. 185,379

2 Claims. (Cl. 132—74.5)

This invention relates broadly to toilet articles and has especial reference to a fountain pencil for the purpose of treating cuticle formed upon the base of the nails so that this cuticle may be 5 readily removed from the finger nails by use of any suitable manicure instrument.

The principal object of the invention is to provide a fountain pencil of the character set forth that includes a barrel and a spring pressed nib 10 having valve members cooperating therewith to control the flow of fluid from the barrel to the pencil and to break the vacuum in the pencil barrel.

Another object of the invention is to provide 15 a fountain pencil of this character which will automatically deliver a measured portion of liquid, such as oil, to the cuticle of the fingers when the barrel is pressed downward by the user, the flow of fluid to and from the nib being regulated 20 by the pressure upon the barrel thereof.

A further object of the invention is to provide 25 a fountain pencil of the character set forth that may be utilized by manicurists for the softening of the cuticle or may be used by any individual 25 for this purpose and that may be readily carried in the purse or in the pocket without soiling the same.

A still further object of the invention is to 30 provide a pencil of this character which includes a simple valve mechanism capable of delivering a measured amount of fluid to the nib of the pencil upon slight pressure upon the barrel thereof when the nib of the pencil is resting upon the finger nail.

An additional object of the invention is to 35 provide a fountain pencil of this character that includes a main valve having ports therein communicating with the barrel and with a central bore formed in the nib so that when said valve

40 is unseated a measured amount of fluid is fed to the pencil nib and when seated positively closes these bores and seals the fluid within the barrel.

A still further object of the invention is to 45 provide a pencil of this character which is positive in its action, is simple in construction, is light in weight and that may be easily and quickly filled.

A further object of the invention is to provide 50 a fountain pencil of this character that includes a ready and sufficient quantity of fluid for a considerable period.

Referring to the drawing:

Figure 1 is a side elevation of my improved pencil with portions thereof broken away to 55 close the valve mechanism thereof;

Figure 2 is a detail view of the pencil and feed valve and showing the ports arranged therein;

Figure 3 is an end view of Figure 2, showing the arrangement of the ports in said valve;

Figure 4 is a greatly enlarged sectional view 5 of the entire pencil and showing the barrel and the positioning of the feed valve and the vacuum release valve, the valves being shown in operative positions; and

Figure 5 is a transverse section taken on the 10 line 5—5 of Figure 1.

Many persons are bothered with a cuticle which grows about the nails adjacent to the flesh thereof, and spoils the appearance of the nails and fingers. The usual practice of removing this 15 cuticle is to use an implement such as an orange wood stick to raise the cuticle and then cut the same away with cuticle scissors or a like implement.

This is not only a tedious operation but is 20 sometimes painful, but in the use of my device the cuticle is softened and may be either readily removed or forced back against the flesh and allowed to wear away.

In detail my improved pencil consists of a 25 suitable barrel 6 having a tapered end section 7 and a capped outer end 8. A cap 9 is also provided to cover the pencil tip when not in use.

Valve members 10 and 11 are positioned within 30 the barrel and operate thru bores formed thru the valve guides 14 and 15, the main valve 10 having a stem 16 and a nib 17 extending therefrom and thru the bore 12 and the nib is provided with a longitudinal port 18 communicating with radial bypass ports 19 formed in the valve, 35 as clearly shown in Figure 2, said valve 10 being capable of seating in the seat 20 formed in the inner face of the section 14.

This feed valve 10 is held normally seated by means of a coil spring 21 surrounding the stem 40 16 and bearing against the back of said valve.

The vacuum release valve 11 is capable of being 45 normally seated in the seat 22 and is held seated by means of the coil spring 23 arranged in the cap 8 of the pencil and said valve is provided with a short stem 24 extending thru the loose bore 13 thru which bore fluid is supplied to the barrel when needed upon removal of the valve 11 from the barrel.

The coil spring 21 normally closes the feed 50 valve 10 and the spring 23 normally closes the valve 11, however, when the pencil nib 17 is applied to the finger and slight pressure is applied to the barrel 6 the feed valve 10 is opened and oil flows to and thru the ports 19 and to the port 55

18 and thence to the tip of the nib whereat it is applied to the cuticle.

- It will be noted that in Figure 1, when both valves are normally seated a slight space exists 5 between the feed valve stem 16 and the vacuum valve stem 24 so that when pressure is applied to the pencil nib the main valve unseats first and then the vacuum valve stem 24 is encountered and the vacuum valve 11 is unseated. Any vacuum which may exist in the barrel is broken and 10 the oil may flow freely thru the ports 18 and 19 to the nib tip, both valves being again seated by their respective springs when pressure is released between the barrel and nib.
- 15 In this manner a positive flow of oil is produced to the nails and a positive discontinuance of this flow is accomplished when the barrel is released due to the tight seating of valve 10 and the sealing of the ports 19 in the valve seat 20.
- 20 I claim and desire to secure by Letters Patent of the United States the following:

1. A cuticle pencil including a barrel; a spring

seated vacuum valve in the upper end of said barrel and having a stem projecting thereinto; a spring seated feed valve in the lower end of said barrel and having a hollow nib protruding therefrom and communicating with a bypass in said feed valve; and a stem on said feed valve in spaced operative relation to the stem of said vacuum valve, whereby the opening of the vacuum valve is subsequent to the opening of the feed valve.

2. A cuticle pencil including a barrel having a feed valve guide and a vacuum valve guide in its opposite ends respectively, with valve seats therein; a valve stem having a hollow nib projecting from said barrel; a feed valve on said stem seated in said feed valve guide and having a bypass into said nib; a spring in said barrel expanding between said vacuum valve guide and said feed valve; and a spring seated vacuum valve having a stem engageable with said feed valve 15 stem.

RAY K. GREGORY.
